UNITED STATES PATENT OFFICE.

EDWARD W. POWELL, OF CHICAGO, ILLINOIS, ASSIGNOR TO PETTIBONE-MULLIKEN COMPANY, A CORPORATION OF NEW YORK.

SWITCH DEVICE.

Application filed January 23, 1928. Serial No. 243,777.

My invention relates more particularly to switchpoints of railway switch devices which, in the switching of trains from a main track to the switch track, are subjected at 5 their pointed extremities to extreme wear by reason of the engagement of the wheel flanges therewith.

My primary object is to reduce the expense incident to such wear of the point rails.

Another object is to provide, as a part of the extremity of the point rail, means for laterally deflecting away from the rail, the flanges of the wheel travelling over the point preferably to such an extent as to ensure 15 against the re-engagement of the wheel flanges with the point rail until these flanges have moved to a position in which they extend opposite a relatively heavy section of the point rail, namely, a portion of the point rail 20 which, by reason of its thickness, may be subjected to great wear without impairing it for properly functioning; and other objects as will be manifest from the following description.

Referring to the accompanying drawings: Figure 1 is a broken plan view of a switch-equipped portion of a railway track and in which my improvement is incorporated. Figure 2 is a plan view of the pointed extremity 30 of the point rail to which my improvement is applied. Figure 3 is a view in side elevation of the point rail of Fig. 2 showing a portion of the main rail with which it cooperates. Figure 4 is a view in side elevation of the 35 main section of the point rail shown in Figs. 2 and 3; and Figures 5, 6 and 7, enlarged sectional views taken at the lines 5, 6 and 7, respectively, on Figs. 2 and 3 and viewed in the direction of the arrows.

In Fig. 1 I have shown a well known arrangement of main line rails together with a switch construction interposed therein. One of the main line rails is represented at 8. The opposite main line rail is formed of rail 45 sections 9 and 10 spaced apart lengthwise and spanned by a point rail 11 of the switch device, the other point rail thereof being represented at 12. The point rails 11 and 12 are connected together, as through the medium of tie bars 13 to cause them to move simultaneously into and out of switching position as is well understood in the art. The main rails 50 of the switch track are represented at 14 and 15, the rail 14 being a continuation of the

point rail 12 and the rail 15 a deflected continuation of the main line rail 9.

In accordance with my invention the point rail 12 which to effect the switching of the train from the main line track onto the switch track in moving to the right in Fig. 1, is moved from the position shown in Fig. 1 into the position shown in Figs. 5, 6 and 7 to extend against the inner side of the main line rail 8, is formed of a main section 15 comprising a base portion 15, web 16, and head 17, its outer side surface being beveled as represented at 16 from a point adjacent its right-hand end in Fig. 1 to the opposite extremity thereof, the head 17 at the pointed extremity of the point rail 12 and a portion of the web 16 thereof being cut away as represented at 18, apertures 19 being formed in the portion of the web forming the base of this recess.

The point rail 12 also comprises a terminal point section represented at 20 which is secured to the point rail section 15 to complete the point portion of the latter as shown particularly in Fig. 2. The section 20 is shown as in the form of a plate containing in its outer surface a recess 21 at which it is seated upon the recessed portion 18 of the main section 15 and to which latter it is secured as by bolts 22 passing through openings 23 in the plate 20 and through the openings 19 in the section 15.

In accordance with my invention the inner side rail-flange-engaging surface of the plate 20, which when the point rail 12 is in switching position extends at an angle to the main line rail 8, instead of being in line with the inner wheel-flange-engaging surface of the main section 15, is out of line therewith and forms the more or less abrupt laterally disposed surface 24 which serves in the engagement of the wheel flanges therewith to deflect 95 the wheels toward the rail sections 9 and 15, the deflecting surface 24 being preferably so formed, as for example as shown, that the flanges of the wheels engaging the switch-point 12 will not re-engage therewith until 100 these wheels have passed a substantial distance to the right in Fig. 2 beyond the section 20 which preferably would be about eight inches long when used in connection with standard railway track construction.

By thus providing for the deflection of the wheels the point rail section 15 may be formed of an ordinary steel rail shaped as described,

as the impact of the flanges against it occurs only at a relatively thick portion of this rail section and which may be subjected to relatively great wear without impairing the proper functioning thereof. The section 20 which provides the relatively sharp extremity of the point rail and takes the initial thrust exerted by the wheel flanges in the switching operation preferably is provided of relatively hard metal, as for example manganese steel, and by reason of the provision of the deflecting surface referred to, may be provided as a comparatively small member which may be provided at relatively small expense, thereby effecting great economy in switch construction, particularly as compared with the common form of switch constructions unprovided with wheel deflecting projections and having their pointed extremities formed of relatively long removable sections of hard metal such as manganese.

The inner wheel-flange-engaging portion of the section 20 and providing the deflecting surface 24 as stated, is preferably beveled as indicated at 25 at the end thereof adjacent the head 17 of the main section 15, to avoid undue obstruction to the travel of trains passing to the left in Fig. 1 from the switch track onto the main track.

While I have illustrated and described a particular embodiment of my invention, I do not wish to be understood as intending to limit it thereto as the same may be variously modified and altered without departing from the spirit of my invention.

What I claim as new, and desire to secure by Letters Patent, is:

1. A point rail of a railway switch formed of a main section and a terminal point section secured to said main section and completing its point portion, said terminal point section having a laterally extending wheel-flange-engaging projection for deflecting the wheel flange laterally in a direction away from the side of said point rail. 40 45

2. A point rail of a railway switch formed of a main section with its upper portion recessed at its terminal end, and a terminal point section located in the recessed portion of said main section and secured thereto and completing its point portion, said terminal point section having a laterally extending wheel-flange-engaging projection for deflecting the wheel flange laterally in a direction away from the side of said point rail. 50 55

3. A point rail of a railway switch formed of a main section having its head portion tapered and terminating in a relatively abrupt point, and a terminal point section secured to said main section and having a relatively sharp pointed extremity and completing the point portion of the point rail, said terminal point section having a relatively abrupt laterally extending wheel-flange-engaging surface merging into the pointed extremity of said terminal point section for deflecting the wheel flange laterally in a direction away from the side of said point rail. 60 65

EDWARD W. POWELL.
